165,389

PHOTOGRAPHIC CONTACT PRINTER

Joseph Palma, Jr., Chicago, Ill., assignor to Ditto,
Incorporated, Chicago, Ill., a corporation of
West Virginia

Application August 9, 1951, Serial No. 16,215

Term of patent 14 years

(Cl. D64—11)

To all whom it may concern:

Be it known that I, Joseph Palma, Jr., a citizen of the United States, residing at Chicago, in the county of Cook and State of Illinois, have invented a new, original, and ornamental Design for a Photographic Contact Printer, of which the following is a specification, reference being had to the accompanying drawings, forming a part thereof, in which:

Fig. 1 is a front perspective view of a photographic contact printer, showing my new design;

Fig. 2 is a side elevation thereof, showing the side not shown in Fig. 1;

Fig. 3 is a rear elevation thereof, and

Fig. 4 is a plan view thereof.

I claim:

The ornamental design for a photographic contact printer, substantially as shown.

JOSEPH PALMA, JR.
